HEAT INSULATING STRUCTURE

Joseph L. Finck, Washington, D. C.

Application March 15, 1932, Serial No. 599,023

5 Claims. (Cl. 189—34)

The present invention relates to heat insulating bodies or structures generally and more particularly to the effective sealing of such bodies or structures so as to prevent the deterioration of the insulating material which is caused by the condensation of moisture upon the insulating material. The present invention is particularly applicable to insulating material or insulating structures employed for refrigerating purposes or the like. Due to the periodic variation of the temperature within or outside of the insulating material, any openings that may reside in the cover of such insulating material will permit the repeated entry into the insulation space of moisture laden air. The moisture from this air deposits upon the insulation material with the result that in the course of a period of time much less than the life of the other parts of the installation, the moisture deposited upon the insulating material will bring about a deterioration of such material and a substantial reduction in the insulating value thereof. The present invention, therefore, comprehends a process and a product in which the insulating material is effectively protected against the deteriorating effects of such moisture deposits by effectively sealing the insulating body or insulating structure.

A further object of the present invention is to provide this effective seal against the ingress of moisture laden air without substantially lowering the insulation value of the body of insulating material or of the insulating structure.

The principles of the present invention may be embodied in a variety of forms. Only a limited number of these forms are disclosed herein and in the accompanying drawing.

Figure 1 shows a longitudinal sectional view of the present invention applied to one type of heat insulating panel;

Figure 2 shows a similar view of another type of panel embodying the principles of the present invention;

Figure 3 shows a similar view of another type of panel embodying the present invention;

Figure 4 shows a refrigerator cabinet and its door embodying the present invention;

Figure 5 shows another type of refrigerator cabinet embodying the present invention;

Figure 6 shows the details of the seal around the edge of the type of panel shown in Figure 1;

Figure 7 is a similar view showing a detail of the seal around the panel of the type shown in Figure 2;

Figure 8 shows the details of the seal around

the door and jamb of the type of refrigerator shown in Figure 4, and

Figure 9 is a view similar to that shown in Figure 8 and showing the details of the seal around the door and jamb of the refrigerator disclosed in Figure 5.

Figure 10 is an enlarged view of one of the joints shown in Figure 6. Figure 11 is an enlarged view of one of the joints shown in Figure 7.

Figures 1, 2 and 3 each show an insulation panel or a panel of insulating material which may be employed in the construction of any type of thermal insulating structure, such as a refrigerating cabinet, a cold storage warehouse, or a refrigerating freight car, or it may be employed in the construction of automobile bodies employed in the transportation of perishable food materials or the like. More specifically, Figure 1 discloses a panel of this type in which the flat surfaces thereof, *a*, *a*, are of sheet metal, the space between these side walls being filled with insulating material *h*. While any type of insulating material may be disposed between the side walls *a* and the insulating material may be introduced into the insulation space in any manner desired, reference is made at this point to the applicant's copending application, Serial No. 318,244, filed November 9, 1928, for a preferred method of filling the insulation space with insulating material. It will be understood, however, that for the purposes of the present invention any other type of insulating material may be introduced into the insulation space in any other manner desired.

The object of the present invention is to provide a seal around the edges of the panel, the seal being so designed and constructed that it assists in the rigidity of the panel and at the same time offers a hermetic seal for the insulation space, without substantially increasing the total conduction of the panel. Consider the detailed process of construction of a panel, such as that shown in Figures 1 or 2. Strips *c* of wood, or other similar material which combines rigidity and high insulating properties, are made to form an open frame. Narrow strips of sheet iron *e*, of say gage #22, are screwed or nailed to the sides of this framework, as shown in the figures.

Next the inner faces as well as the sides (which are already covered with iron strips *e*) of this wooden frame are covered with a thin metal foil *d*, such as lead, tin, aluminum or the like. A sheet metal side wall *a* is now placed against the wooden frame as shown and the edge *g* (Figs. 6 and 7) is soldered or welded. Here the func-

tion of the metal strips *e* may be explained. In attempting to solder or weld a thin metal foil to a heavy metal, difficulties are encountered because the metal foil melts away too rapidly. 5 By placing the metal foil between two other heavy pieces of metal, the soldering or welding proceeds very easily.

It is now possible to fill the panel with the insulating material. Although any material and 10 process may be employed for filling these panels, I prefer to fill them in a manner indicated in my co-pending application, Serial No. 318,244, filed November 9, 1928. This method consists first in applying a coating of shellac or other 15 suitable material to the exposed surface of the sheet metal foil *a*, and if desired also to the interior surface of the metal foil *d*. Also, the second side of the finished panel should be covered with shellac on that surface which will face 20 the interior of the panel. Second, the panel is then filled with loose fibrous material (cotton, jute, etc.) in which a granulated rosin or similar material is scattered throughout the mass. Lastly, the second side of the panel is set in place 25 and soldered, or welded along the edge *g*. A small opening should be left open temporarily for the following reason. In my copending application, mentioned above, I propose to heat this panel to about 100° C. for about an hour or 30 so, and then allow to cool. This heating causes the shellac on the interior walls to become tacky, and also partly melts the dispersed granulated rosin. On cooling, the fibers in contact with 35 the walls will adhere firmly to the walls, and within the fibrous mass the granulated rosin will cause a matting of the fibers. In this way the insulation is held in place and withstands settling, which ordinarily arises from vibrations or shocks. The small opening is now closed.

40 It will be seen that by means of this process a panel is obtained in which the insulating material within the insulation space is completely and hermetically sealed by means of a metal surface which is impermeable to moisture and the insulating material is thereby protected against the deteriorating effects of such moisture.

If desired, the metal foil *d* may be additionally anchored and retained between the strips *e* and the superposed portion of the metal walls *a* by 50 additionally brazing or spot welding to the strips *e* the portions of the side walls *a*, which overlie the strips *e*. It will further be understood that if desired the metal foil *d* may be applied to the wooden strips *c* by an adhesive.

55 Figure 2 shows an insulation panel in which the side walls *a*' are made of wood or analogous material, such as composition board. In such constructions the walls *a*' are preferably covered on their inner faces with metal foil *b*. The edges of the insulation space in this construction are closed and sealed in a manner closely analogous to that disclosed in Figures 1 and 6. Similar wooden strips *c* are employed, these strips being similarly covered with metal foil *d*, the strips *c* also having attached to the longitudinal edges the sheet metal strips *e*. Corresponding sheet metal strips *f* are attached to the adjacent edge portions of the inner faces of the side walls *a*'. The edge portions of the metal foil *b* as well as of the metal foil *d* projects into the space between the adjacent metal strips *e* and *f*. These metal strips are joined together and with the edges of the metal foils *b* and *d* by means of the soldered or welded joint *g*.

70 75 Figure 3 shows a panel which combines the

features of construction shown in each of Figures 1 and 2 for the reason that one side wall *a* is of sheet metal and the other side wall *a*' is of wood or similar material. In this type of construction, therefore, the side wall *a*' is provided with metal foil *b*, the edges of which fall into the space between the metal strips *e* and *f* and the sealing is effected on this side of the panel in the manner disclosed in Figure 7, whereas the sealing effected on the other side of the panel is in the manner disclosed in Figure 6.

The sealing edges shown in these panels have a very low thermal conductance and add but slightly to the conductance of the entire panel. It is found, for example, in the type of panel shown in Figures 1 and 6 that in a panel having a thickness of four inches and having an area of 4 x 8 feet and employing for its side walls *a* sheet steel having a thickness of 0.03 inches, the edge seal may be effected by employing a wood strip 95 having a width of 4 inches to fill the space between the side walls *a* for a thickness of 1 inch and a lead foil having a thickness of 0.003 inches. When the type of insulating material disclosed by my co-pending application referred to above 100 is employed the conductance of the insulating material per se in a panel of these dimensions is 2.24 B.t.u. per hour per degree F., across the surface of the panel. The conductance of the wood strips *c* is 0.40 B.t.u. per hour per degree 105 F. and the conductance of the lead foil *d* is 0.345 B.t.u. per hour per degree F. It will be seen, therefore, that the total conductance of this panel is 2.98 B.t.u. per hour per degree F., namely 0.72 B.t.u. per hour per degree F. greater than the 110 conductance of the insulating material. If, however, a similar panel should be constructed having for its sealing edge the same material as that employed in the side walls *a* of the panel, the conductance of the sealing edge itself would 115 be 4.50 B.t.u. per hour per degree F. or twice as great as the conductance of the insulating material. Such a seal would clearly nullify the insulating effect of the insulating material. It will be seen, therefore, that by means of the present 120 invention a metallic and hermetic sealing is obtained which has a negligible effect upon the insulating properties of the panel.

Figure 4 shows a refrigerating cabinet of the type disclosed in my above mentioned co-pending application and in my application, Serial No. 242,776, filed December 27, 1927. This figure shows a metallic refrigerator cabinet where the inner and outer containers which form the insulation space between them as well as the inner 130 and outer face of the door are made of sheet metal such as iron, steel or the like. Figure 4 shows the application of the present invention to the door and jamb of this cabinet. Figure 8 is a detailed view of such door and jamb and 135 shows a construction substantially identical with that shown in Figure 6 except for the fact that the strips *c* are so shaped that the door and jamb properly fit one within the other.

Figure 5 shows another type of refrigerator 140 cabinet in which the inner container *a* is made of sheet metal and the outer container is made of wood or similar material *a*'.

Figure 9 shows the application of the present invention to the jamb and door of this refrigerator. It also shows the manner of assembling the outer walls of this refrigerator. It will be seen that the outer walls *a*' have their inner faces covered with metal foil *b* which extends along the mitered edges of the walls *a*', which are 145 150

covered by the metal strips *l* and *m* and which are attached to the adjacent mitered faces of the walls *a'*. In assembling these adjacent walls the edge portions of the metal foil *b* is held between the metal strips *l* and *m* and the strips *l* and *m* together with the edge portions of the metal foil *b* are welded together at *n*. The corner structure is reinforced by the angle iron *o* as shown. The reference character *p* merely designates a small wooden block suitably shaped to fit into the corners of the structures and to increase the rigidity of the structure.

I claim:

- 15 1. A refrigerator wall construction having an inner metal wall member, an outer metal wall member spaced therefrom, heat insulating material disposed between said wall members, and a closure for said space comprising a bar of non-metallic material and a strip of thin sheet metal carried by said bar on the side thereof facing said space, said strip being welded to said metal walls, along the marginal edges thereof, whereby the welding operation may be performed on the exterior of the wall structure.
- 20 2. A refrigerator wall construction having an inner metal wall member, an outer metal wall member spaced therefrom, heat insulating material disposed between said wall members, and a closure for said space comprising a bar of rigid insulating material disposed between the edge portion of said walls, said bar having its interior face covered by metal foil, said metal foil being welded to adjacent marginal edges of said walls whereby the welding operation may be performed on the exterior of the wall structure.

3. A refrigerator wall construction having an inner metal wall member, an outer metal wall member spaced therefrom, heat insulating material disposed between said wall members, and a closure for said space comprising a bar of rigid insulating material disposed between the edge portions of said walls, said bar carrying sheet metal strips on its lateral faces and metal foil on its inner face, said metal foil overlapping onto said metal strips, said strips and metal foil being soldered or welded to the marginal edges of said metal walls, whereby the welding operation may be performed on the exterior of the wall structure.

4. A refrigerator wall construction having spaced inner and outer wall members, said wall members having sheet metal marginal portions, and a closure for the space between said wall members comprising a bar of rigid non-metallic material carrying a strip of thin sheet metal on its interior face, the edge portions of said strip being soldered or welded to said marginal portions, whereby the soldering or welding may be performed on the exterior of the wall structure.

5. A refrigerator wall construction having spaced inner and outer walls of rigid non-metallic material, carrying a strip of sheet metal on the marginal portions of their interior faces, metal foil carried by the inner faces of said walls and overlapping onto said sheet metal strips, and a closure for the space between said walls comprising a rigid bar of non-metallic material having metal foil on its interior face, the metal foil being welded or soldered to said marginal sheet metal strips.
